UNITED STATES PATENT OFFICE.

JOHN P. WEIS, OF NYACK, NEW YORK, ASSIGNOR TO METROPOLITAN SEWING MACHINE CORPORATION, OF NYACK, NEW YORK, A CORPORATION OF DELAWARE.

LOOPER MECHANISM FOR SEWING MACHINES.

Application filed October 9, 1923. Serial No. 667,454.

To all whom it may concern:

Be it known that I, JOHN P. WEIS, a citizen of the United States, residing at Nyack, in the county of Rockland and State of New York, have invented certain new and useful Improvements in Looper Mechanism for Sewing Machines, of which the following is a specification.

This invention relates to sewing machines, 10 and more particularly to that type or style of machine having a hollow supporting member or horn, which in the present instance is cylindrical in construction, where- 15 in the feeding, looper and thread controlled mechanism are contained and operated for the purpose of working upon or forming tubular goods, an object of the invention being to provide a sewing machine adapted to operate efficiently at high speed and 20 comprising improved looper mechanism, wherein means is provided for adjusting or varying the elliptical path of movement of the looper so as to conform to varying thicknesses or gauges of needle, the present 25 application containing matter in part embodied in my co-pending application, Serial No. 481,032, filed June 28, 1921.

A further object of this invention is to 30 provide a sewing machine having improved looper mechanism for cooperation with the needles in the formation of stitches, which in the preferred form comprises means for making preferably two parallel lines of double thread chain stitches, there being 35 two loopers, each carrying a looper thread. The same mechanism may be used for making two lines of single-thread chain stitches by omitting the looper threads. This looper mechanism can also be used for making 40 what is commonly called the twin-needle, three-thread covering stitch having a thread carrying looper cooperating with two spaced thread-carrying needles, wherein the formation of the stitch is accomplished by having 45 the looper thread concatenated with each of the needle thread loops formed by the needle threads, leaving the looper thread lying in a zig-zag form from one line of needle stitches to the other. Such loopers 50 may also be used with the vibrating needle or needles for the purpose of making zig-zag stitches.

In the present instance a very simple high speed looper mechanism is provided which 55 will operate one or more loopers, the same

having means whereby each of the loopers may be adjusted to suit different needle gauges, or different kinds of stitch formation, the construction being such as to permit for instance the same pair of loopers 60 to be adjusted to cooperate with needles spaced for making very narrow spaced rows of stitches as well as very wide spaced rows. This is a very important improve- 65 ment because machines now in commercial use require a variety of loopers, sometimes as many as 25 or more different styles to accommodate various needle gauges, whereas in the present improvement a single style of looper may be used either for the front 70 or back looper and furthermore may be adjusted to suit or accommodate any of the needle gauges.

A four-motion elliptical movement is given to the loopers so that they travel in 75 the rear of the needles when entering the needle loops as they move in one direction and return to their initial position in front of the needles, so that the needles coat with 80 the back of the looper to enter between the looper and the looper thread.

In order that the loopers may coat with 85 thin or thick needles, I have provided an adjusting means to increase or decrease the movement of the loopers from front to rear of the needles, such means also being accessible to the operator from the outside 90 of the machine. The elliptical movement of the loopers is obtained from a single crank and connection, connected in such a way with the crank shaft and side wall of the sewing machine as to provide a very rigid construction with a minimum of weight.

A further object of this invention is to 95 provide a sewing machine having improved means for controlling or taking up the looper thread, such means being accessibly located adjacent to the free end of the hollow supporting member for the looper mechanism.

Other objects of this invention will appear in the following description and appended claims, reference being had to the 105 accompanying drawings forming a part of this specification, wherein like reference characters indicate corresponding parts in the several views, and wherein Fig. 1 is a side elevation of the machine with the end 110 cap or cover of the looper mechanism shown

in dotted lines and the transmitter shown in operating position under the machine, but detached from the work table to more clearly illustrate the relation of the transmitter 5 with the sewing machine; Fig. 2 is a front perspective view of the sewing machine, transmitter and treadle connected for operating the same; Fig. 3 is a perspective view of the end cap for covering the looper and 10 thread controlling mechanisms; Fig. 4 is an end view of the needle bar operating mechanism, portions of the needle bar bushings, oil cup and needle bar being broken away to more clearly show the construction, 15 and a portion of the arm and crank shaft shown in broken lines; Fig. 5 is a back elevation of the machine, illustrating the connections for the needle drive and a portion of the looper and feed actuating mechanisms; 20 Fig. 6 is a side elevation of the feeding mechanism, parts being broken away to clearly show the assemblage; the overhanging portion of the arm and the machine frame being indicated in broken lines; 25 Fig. 7 is a top plan view of the cylindrical portion of the machine illustrating the looper mechanism; Fig. 8 is a side elevation of the mechanism shown in Fig. 7, the overhanging arm of the machine being indicated in broken lines; 30 Fig. 9 is an end elevation of the cylinder, illustrating the mounting of the loopers and needle guards; Fig. 10 is a perspective view of the circular holder for the loopers; Fig. 11 is a perspective view of the arm which supports the 35 circular holder for the loopers; Fig. 12 is a perspective view of a looper; Fig. 13 is a perspective view of the needle guard and holder; Fig. 14 is a detail view partly 40 in section, illustrating a looper; Fig. 15 is a detail plan view of a form of looper; Fig. 16 is a detail view of the lower end of the looper actuating connection, a portion being broken away to clearly show the assemblage 45 of the parts; Fig. 17 is an end elevation of the cylinder and looper actuating means, partly in section taken on lines 17—17 of Fig. 7; Fig. 18 illustrates diagrammatically the movement of the looper actuating means; Fig. 19 illustrates diagrammatically the elliptical path of movement of the loopers; Fig. 20 is a diagrammatic view illustrating the manner in which 50 adjustment of the looper mechanism may be made in order to change the oscillation of the loopers from front to rear of the needles, for cooperation of the loopers with needles of different sizes; Fig. 21 is an end view of the cylinder showing the looper thread controlling means, with the looper in its extreme forward position; Fig. 22 is a view of the part shown in Fig. 21 with the looper in position for the needle to enter between it and a strand of the looper thread, also 55 showing the thread clamped by the thread controlling mechanism in full and dotted line position, the full lines representing the thread being clamped while the needle is moving downward and the looper is moving backward, and the dotted line position representing the thread clamp open for free movement of the looper thread while the looper is moving in the opposite direction; Fig. 23 is a view similar to Figs. 21 and 22, but showing the looper in its rearmost position, where it shifts from front to rear of the needles, and at which time the thread clamp is open as the needle starts to rise and the looper moves toward it to enter the 60 needle loop; Fig. 24 is a perspective view of a group of parts of the looper thread controlling means; Fig. 25 is a fragmentary perspective view of the end of the cylinder, showing a portion of the throat plate, looper thread clamping means, and the 65 looper thread guide tubes which conduct the thread from the rear of the machine to the thread controlling mechanism; Fig. 26 is a perspective view of the looper thread take-up or controller; and Fig. 27 is a detail elevation view of the looper thread guide tubes, thread clamp, and a portion of a rock lever with guide eyes for conducting the 70 thread to the loopers.

Before explaining in detail the present improvement and mode of operation thereof, I desire to have it understood that the invention is not limited to the details of construction and arrangement of parts which are illustrated in the accompanying drawings, 75 since the invention is capable of other embodiments, and that the phraseology which I employ is for the purpose of description and not of limitation.

Referring to the drawings, it will be seen that the present machine is mounted upon a suitable table 1 and comprises a machine frame having flanges 2 and 3 for supporting and securing the machine to the table. The main portion of the frame is preferably 80 of hollow rectangular construction, closed at the bottom, and having a front wall 4 and a rear wall 5 provided with an opening 6 adapted to be closed by means of a cover plate 7 attached thereto in any suitable manner. The machine frame with its enclosing walls forms of itself an oil reservoir, and pump mechanism (not shown) is located therein for lubricating the various 85 bearings of the machine. The machine frame forms an oil tight chamber against the escape of oil to the outside. This cover plate is provided with a hollow projecting portion 8 within which operates a stop lever for the stopping and starting mechanism 90 of the machine. The front wall 4 of the frame is provided with a boss 11 bored to receive a cylinder 12. The side wall 13 of the frame is provided with a boss 14 for receiving one of the crank shaft bushings 15, 95

the opposite side wall having secured thereto a suitable belt guard 22 which covers the driving belt 23. The frame is provided with inwardly projecting bosses 26 and 29 bored 5 to receive bushings for supporting the crank shaft of the machine. Projecting from the front wall 4 is an overhanging arm 32 terminating in a bearing 33.

The overhanging arm 32 is provided 10 with suitable bearings 37 and 38 for a needle operating rock shaft 39. Secured to the forward end of the rock shaft 39 by screws 40 is a needle bar operating arm 41. The end of the shaft 39 is tapped to receive a 15 screw 42 and a thrust washer 43 thereby to prevent end movement of the arm 41 on the shaft 39. At the outer end of the arm 41 by means of a joint pin 44 is secured a link 45, the bottom end thereof being connected by means of a joint pin 46 to an end 20 piece 47 tapped into the needle bar 48 and clamped with a lock nut 49. The needle bar is hollow and the lower end is tapped to receive the needle holder 50 which carries 25 the needles 51. The needle bar is provided with two openings 52, the upper one being an inlet and the lower one an outlet for oil for the purpose of internally oiling the upper and lower needle bar bushings, 53 30 and 54.

Secured to the top of the upper bushing 54 is an oil cup 55 provided with a felt oiler, carrying sufficient lubricant for the needle bar, but preventing the oil from dripping 35 and soiling the goods. An intermediate felt oiler 56 is provided between the two bushings. These felt oilers wipe the needle bar in its reciprocating movement, keeping it 40 clean and properly lubricated.

To the rear end of the rock shaft 39, adjacent to the bearing 37 is secured a crank arm 57 and ball stud 58, to which is connected the upper end of a ball connection 59. The lower end 60 also has a ball socket to fit over 45 the ball 61 of the crank shaft.

A presser bar 183 reciprocates vertically in a bushing 187 carried by the bearing 33, and a presser foot 188 is secured to the lower 50 end of the presser bar. Above this bearing is a rectangular opening 34 through which the presser foot lifting member 180 operates.

Mounted in end bearings 15 and 99 of the frame, and in suitable bearings in bosses 55 26 and 29 is a transversely extending crank shaft 62, 63 having a clutch wheel 93 provided with a suitable belt groove over which passes belt 23 of the transmitter.

The power transmitter comprises in general 60 a main bracket 143 secured to the bottom of the table in any suitable manner, the bracket having an arm bored to receive a shaft 144. Upon this shaft is mounted a cone pulley 145 over which operates a belt 146 for transmitting power from any 65 suitable line shaft to the pulley. The belt

23 is driven by a pulley 149 for operating the sewing machine. Suitable clutch mechanism for the pulleys 145 and 149 is provided which is controlled by means of a rod 156 connected to a floor treadle 159. A further 70 detailed description of the power transmitter mechanism is not deemed necessary herein since the same is fully described in my co-pending application.

Referring to Fig. 6, a four-motion feeding mechanism coacting with the presser foot is provided for feeding the work through the machine. This mechanism comprises a feed dog 208, which may be of any preferred form to suit the character of work. 75 This feed dog is adjustably and detachably mounted upon a feed bar 213, which is rockably supported in the cylinder 12 by a swinging yoke link 220 embracing the bar. Four-motion movements are transmitted to 80 the feed bar by the ball crank 69 of the crank shaft operating in the bearing 230 of the feed lever 231. The rear end of the feed bar 213 is connected to the feed lever 231 by means of a joint pin 233. Mechanism 85 is provided for adjusting and regulating the length of stitch or the throw of the feed dog, preferably by means of self-locking adjusting mechanism. A detailed description of this mechanism is not deemed 90 necessary herein, the same being fully described in my co-pending divisional application Serial No. 667,453 filed October 9, 1923.

It will be noted that the feed bar is upwardly inclined at its rear end and is trough shaped from end to end, whereby an open flow of lubricant is conducted thru the cylinder to the bearings and since the cylinder is supported in inclined position the lubricant will flow back thru the bottom of the cylinder into the machine frame. The motion of the feed bar throws the oil to the adjacent operating or bearing parts. By means of the threaded tubes and the location of the thread handling mechanism, the oil will not contact with the thread, and at the same time this mechanism is accessible 105 from the free end of the cylinder.

Referring particularly to Figs. 7 to 20 110 inclusive, the looper mechanism is operated by the ball crank 67 of the crank shaft, having connected thereto a ball joint 265 of the lever connection 266, the lower end of which has a ball socket 267 for receiving the ball 268 of the arm 269 clamped on the rock shaft 270 which is supported in the bearings 271 of a yoke bracket 272 provided with a tapered shank 273 adjustably secured in the wall 13 of the machine frame by two 115 screws 274. By loosening these two screws, and inserting a screw driver in the slot 274^a, the yoke bracket 272 may be turned so as to tilt the position of the rock shaft 270 from the full line horizontal position 120 125 130

indicated in Fig. 20 to the dotted line position, such line bearing the numeral 270^a corresponding to the axis of the shaft 270. When adjusted to the full line position the 5 swinging movement of the ball 268 is perpendicular to the shaft 270, as represented by the full line 268^a in the diagram, Fig. 20, whereas if the shaft 270 is adjusted angularly as for instance to the dotted line 10 position 270^b, the ball 268 will swing at an angle from the perpendicular, as represented by the dotted lines 268^b. The tapered shank of the yoke 273, is represented by the circle 15 273^a in the diagram. The arm 269 is clamped to the shaft 270 by a screw 275, and is held against sidewise movement by the bearings 271, one on each side of the arm.

The ball socket 267 comprises a cap forming the lower portion of the socket 276 20 secured to the connection 266 by screws 277. This cap is bifurcated to receive a block 278 pivotally supported by a pair of conical screws 279. Clamp screws 280 clamp the conical screws in adjusted position so that 25 the block 278 may rock on the screws without side shake. This block is bored at right angles to the conical sockets for the screws to receive a looper shaft rocking pin 281 securely clamped to the rear end of the 30 looper shaft 282 as by a clamp screw 283. The pin 281 is provided at one end with a head 284 to limit the endwise adjustment of the pin in one direction and to prevent the pin striking the inclined surface 285 of 35 the cap 276. In the present instance the looper shaft is made in two parts, the rear end 282 being of larger diameter than the forward extension 292, the parts being connected in any suitable manner.

40 The rear shaft portion 282 operates in a bearing 286 secured in the cylinder 12 by screws 287, the bearing having an opening 288 at the top to provide working space for the feed bar and having two saw cuts 289, 45 in the front and rear wall diametrically opposite the hole in which the shaft 282 operates. Clamping screws 290 are provided to adjust the saw cuts for adjusting the bearing 286 to fit the shaft 282 thereby taking up wear. The rear wall of the bearing 286 is recessed at 291 to provide clearance for the bottom cap 276 of the ball socket.

Fig. 18 illustrates diagrammatically the 55 operation of the looper operating means above described. The circle A indicates the motion of the ball crank 67, indicated by B. The line C represents the connection 266, and the ball 268 is represented by D, and the connection between the block 278 and the 60 pin 281 is indicated by E. The direction of rotation of the crank shaft is indicated by the arrow in Fig. 18.

Referring to the diagrams of Fig. 18, the 65 action of the looper operating means is as follows: As the shaft rotates from F to G

the bottom end of the connection E shifts from the position H in the diagram to the position I, bringing the connection C to the perpendicular position, and the ball D upon which the lever C is fulcrumed, from the 70 central position J to the lowest position K. Further rotation of the shaft brings the crank B from the position G to the position L, and the connection E to the point M. Further rotation of the shaft brings the 75 crank B from the position L to the highest position N and the connection E to the position O, and the ball D to the position P.

Further rotation of the shaft brings the 80 crank B from the position N to the starting position B, and the ball D to the position J, and the connection E to the position H completing a cycle of movement which gives to the looper the elliptical movement as indicated by the lines Q of the diagram. 85

From the foregoing it will be seen that the ball 268 carried by the arm 269 secured to the rock shaft 270 forms a fulcrum for the lever connection 266 which is reciprocated by the ball crank 67, the center of the fulcrum formed by the ball 268 being relatively close to the connection made between the looper shaft pin 281 and the block 278. The vibratory movement of the loopers, indicated in the diagram of Fig. 18 at H and M 95 represents the movements of the looper from front to rear of the needle, while the movement of the looper into and out of the needle loops is indicated in the diagram at I and O. The path of movement of the looper may 100 be varied to accommodate varying needle sizes or thicknesses as shown by the diagrams of Figs. 19 and 20, one having a perpendicular line passing through the major axis of the elliptical path, and the other having an inclined line passing through the major axis of the elliptical path. The perpendicular position of the elliptical path represents the movement given to the loopers when coacting with a relatively thin needle, 105 while the angular position of the elliptical path represents the movement given to the loopers when operating with a thick needle. It will be seen that the distance from R to S is greater than the distance from T 110 to U in Fig. 19, which distance is increased by reason of the shaft 270 being adjusted to the angular dotted line position 270^b shown in Fig. 20, whereby the ball 268 carried by the arm 269 swings on the angular line 268^b, thus 115 shifting the elliptical path from the perpendicular to the angular position and utilizing a portion of the vertical reciprocation for the horizontal vibration of the looper. 120

Thus where a relatively thin small gauge 125 needle is used the movement of the looper from front to rear thereof is shown from W to X in Fig. 19, while if a larger needle is used the required angular adjustment of the elliptical path of movement of the looper 130

will increase the vibratory movement of the looper as from Y to Z, Fig. 19, so as to enable the same to coact with the thicker needle at the front and rear thereof.

5 The forward end of the looper shaft 292 is supported in the bearing 248 secured in the cylinder 12 by the screws 293. Secured to the free end of the shaft 292 by the clamp screw 294 is a crank arm 295 to which is 10 attached by a screw 297 for vertical adjustment a circular holder or carrier 296 for the loopers. The clamp screw 294 in the aperture 299, Fig. 11, adjustably clamps the arm on the looper shaft, the arm having a 15 saw cut 300 permitting this adjustment. The clamp screw 297 of the circular holder for the loopers is screwed into the aperture 301 of the sleeve, and the side walls of the recess 302 straddle the side walls 303 of the lug 20 304 of the supporting arm for the looper carrier, permitting vertical adjustment of the carrier and loopers. This circular or ring shaped carrier or holder is cut away to form end portions 305 and 306 to give working 25 space for the needles and loopers, and the hole 307 also provides clearance for the needles. Adjacent to the end 305 are two tapped holes 308 for the reception of screws 309 and 310, one adjustably securing a 30 thread carrying looper 311, and the other adjustably securing a like thread carrying looper 312 to the front and rear walls of the ring shaped looper carrier 296.

In the description of the stitching mechanism the term "forward" is herein used to 35 refer to the direction in which the looper points, the term "backward" to the opposite direction of the looper movement. With reference to the terms front and rear of 40 the needles, "front" is intended to mean the side facing the operator, while "rear" refers to the reverse side of the needle.

The loopers 311 and 312 are identical and 45 comprise a blade 313 terminating in a point 314, and an undercut thread groove 315 extending from the front eye 316 to the rear eye 317.

The groove 315 of the looper, as shown 50 in Fig. 14, is constructed with an overlapping wall 315^a, which acts to retain the thread in the groove and prevents it from slipping out of the groove and extending in a straight line between eyes 316 and 317. It has been found in practice that where a 55 groove is provided on the flat face or side of a circular looper, that the thread has a tendency to extend across the arc of the looper thereby interfering with the needle loops. The undercut groove 315 however, prevents 60 the looper thread from getting out of the groove, thereby preventing the skipping of the stitches, the breaking of the needle and looper thread, and enabling the machine to produce more uniform stitching. As shown 65 in Fig. 15, the looper blade may be offset at

316^a for the purpose of creating a back drag on the needle loops. A looper of this construction is often used in a twin needle machine for making ornamental covering stitch. The shank is segmentally slotted at 318 for 70 the screws 309 and 310, and the bottom portion 319 of the shank is circularly formed in order to fit snugly against either the annular flange 320 on one side or the annular flange 321 on the other side of the carrier 296, 75 thereby preventing the loopers from movement relative to the carrier.

Thus it will be seen that I have provided a looper of very simple and durable construction, capable of a wide range of adjustment, whereby a single style or size of looper may be used with different needle gauges, or for different stitch formation, thus avoiding the necessity of providing separate loopers of different sizes or shapes 85 for every different spacing of needles or needle gauge or character of work.

The holes 322 adjacent to the end 306 of the ring shaped or curved holder receive screws 323 and 324 for adjustably attaching the needle guard holders 325 and 326, each holder having a bent wire 327, adjustably secured therein, each wire having a tapered point 327^a and being so shaped as to act as a needle guard to control the 90 needles in case they deflect out of the vertical path and to position them properly with respect to the point of the looper, thus overcoming the skipping of stitches and breaking 95 of needles.

The holders comprise a head 328 within 100 which the wires 327 are secured, and a flattened shank 329 slotted at 330 for the reception of screw 323 or 324 for securely fastening the needle guide holders to the circular holder 296. The circular portions 331 of the shanks of the holders fit snugly against the flanges of the carrier at 332 and 333 to prevent the guards 327 from shifting relatively to the carrier. Thus it will be 105 seen from this construction that the needle guards may be adjusted as desired for all needle gauges and for all sizes of needles, the needle guards and loopers being adjustable one relatively to the other or both relatively to each other.

Coacting with the stitching and feeding mechanism is a throat plate 334, see Fig. 25, secured to the forward bearing 248 by screws 335, Fig. 1. The throat plate is provided 120 with the usual feed slots 337 through which operate the serrated surfaces 336 of the feed dog 208, the throat plate also being provided with the usual needle holes (not shown) 125 through which the needles operate. The throat plate is of segmental construction forming with the cylinder 12 a complete circle when attached thereto, the cylinder being cut away on the lines 338—338 to receive the throat plate. A projecting tongue 130

338^a of the throat plate cooperates with a groove formed in the cylinder, Fig. 8, so that the projecting portion 339 overlaps the tongue 338^a, thereby securely holding the rear end of the plate from tipping or moving when the pressure of the foot is brought to bear upon the outer overhanging end of the throat plate.

Referring particularly to Figs. 1, 2 and 3, the forwardly extending end 340 of the throat plate is provided with beveled or inclined edges 341, and an end cap or cover 343 fits thereover, the dove-tailed grooves 342 of the cap cooperating with the inclined portions 341 and hence the same may be shifted on and off the forward end of the throat plate. The side walls of the cap 344 are partially slotted to make them flexible so that the cap will yield and properly fit over the beveled or inclined edges of the throat plate. The end cap is hollow to provide free working space for the loopers and other parts adjacent thereto. In order to secure the cap 343 to the cylinder and prevent it from becoming disengaged from the throat plate during the operation of the machine the cap is provided with suitable locking means comprising a lock spring 343^b projecting through an opening 343^a for convenient manipulation by the operator, the cap being removed by pressing inward on the spring to disengage the hook end 343^c from a notch 343^d formed in the side wall of the cylinder 12, see Figs. 7 and 8. This lock spring is suitably secured inside of the end cap as by a screw 343^e, Fig. 3.

As illustrated in Figs. 1 and 25, the cylinder 12 may be provided at its forward end with a projecting portion 345 extending outwardly to correspond in length approximately with the overhanging portion 340 of the throat plate, the extension 345 being provided with an end wall 346 to prevent lubricant from escaping, the bearing 247 having a hole 482 to allow the lubricant to flow back into the cylinder in rear of the bearing. The curved side walls 347 of this extension are adapted to lie in juxtaposition to the curved walls of the cap 343 thereby forming a support upon which the bottom edge of the end cap rests.

It will be seen that by reason of the fact that the feeding and looper mechanisms are arranged and supported within the cylinder 12, the same having the enlarged opening 12^a covered by the throat plate extending a considerable distance in the rear of the needles I may do away with the use of a cover plate, and as a result of this construction greater rigidity of the parts is secured, as well as free access to the interior of the cylinder, thus eliminating loose parts with the added advantage of using a cylinder of equal diameter throughout its length.

The cylinder is preferably constructed of steel tubing of small diameter. Such tubular work may be handled with greater facility than the usual casting which is tapered from the free end toward the machine frame, and at the same time giving the increased advantage of greater strength and rigidity. In the present machine the cylinder is detachably secured in the boss 11 by spot clamping screws 349, permitting the cylinder to be removed and replaced by disconnecting the operating means for the looper and feed within the rear trunk of the machine. To prevent the leakage of oil between the cylinder 12 and the boss 11 a wick 350 of suitable material is provided which fits into a groove of the cylinder 12 to form a leak-proof joint between the parts.

Referring to Figs. 2, 21, 22, 23, 24, 25, 26 and 27, improved means for controlling the looper threads is provided. Secured to the end bearing 248 is a two-arm rock lever 351, supported by the shoulder screw 352 screw threaded into the end bearing. An arm 353 of the rock lever carries at its free end a flared portion 354, projecting from one side thereof and having a tapered inclined or cam surface 355 terminating in a flat surface 356, Fig. 24. The upper edge 357 of the arm 353 is adapted to coact with the rounded end 358 of the cam 359 adjustably secured to the looper shaft 292 adjacent to the outside face of the end bearing 248 by set screws passing through the tapped holes 360. The cam 359 rocks the lever on the screw 352 as required to control the looper thread or threads, and swings the lever downwardly away from the looper shaft 292. On the return movement, in order to keep the lever in contact with the coacting surface of the cam 359 a flat spring 361, having its free end resting against the upper portion 362 of an arm 363 of the rock lever 351 is provided. This spring is clamped by a screw 364 into a T-slot 365 of the end bearing 248, as shown in Fig. 25. The spring 361 has a plate 366 attached to it to provide a better clamping surface for the screw 364. At the top of the arm 363 I provide, adjacent to the portion 362 co-acting with the spring, a wall 367 having an aperture 368 to receive the body 369 of the screw 370, while an opposed wall 371 has an aligned aperture screw threaded to receive the threaded end 372 of the screw 370. The walls 367 and 371 are spaced at 373 to receive a rocking plate 374 having an aperture 375 for the screw 370 which rockably supports the plate. The purpose of this rocking plate 374 is to act upon the looper threads and clamp them against the surface 376 of the inner wall of the cylinder 12. The wall 371 is cut out to form two lugs 377 and a space 378 therebetween for the passage of thread, these lugs or projections 377 acting as separators for the

looper threads to prevent them from tangling and to so control and guide the threads one above and the other below the center line of the rocking plate 374 that equal pressure will be imparted to each thread irrespective of the diameters of the threads relative to each other.

10 Adjacent to the wall 371 is a slot 379 and an opposed wall 380 is provided with a thread eye, and an inclined thread slot 381 in the right angled wall 383 leading to the top edge 382 permits the threading of the eyelet in the wall 380. The wall 383 has a second slot 384 leading from the thread hole 15 385 in the end wall 386, and also emerging at the top 382 to permit the thread to be inserted in the hole 385.

20 Between the walls 380 and 386 operates the looper thread take-up or controller, comprising a circular shank at 387 provided with an elongated slot 388, through which passes a clamp screw 389, Fig. 1, for securing it to the rounded surface 390 of the arm 25 295, Fig. 11, carrying the loopers, the screw 389 fitting into the tapped hole 391. The thread controller is curved at 392, reversely to the curve at 387 and is bent in a half-loop at 393, and forms with a curved portion 394, a neck 396, and a curved shoulder 395, terminating in a point 397. The controller is so shaped as to properly act upon the looper thread or threads for controlling the same during the stitch formation.

30 From the foregoing it will be seen that I have provided a very simple, compact, and reliable means for controlling the looper threads, accessibly located in and covered by the end cap of the machine, and comprising a thread clamp or nipper 374 and a thread take-up or controller 387 to give and take-up thread at the desired intervals of each stitch forming cycle. The improved location of the parts offers advantages in threading and adjustment, one of the important advantages residing in the fact that when the looper thread breaks, the broken end of the thread usually lies close to the looper and hence rethreading in the present machine is easy due to the convenient location of the parts. Heretofore thread controlling mechanisms have been located in the cylinder or at the rear of the machine, thereby rendering the parts very inaccessible. Usually action on the thread 40 of the thread-controlling mechanism causes breakage of the thread where weak spots or knots occur in the thread, and when so located, loss of time occurred in the rethreading. All such loss of time is done away with in the present improvement on account of the thread-controller being located at the stitching position. By reason of this construction it is possible to time the action of the cam 359 with respect to the movement of the loopers so that its end 50 55 60 65 358

will coat with the arm 353 of the lever 351 to permit the nipper or clamp 374 to hold the looper threads tightly between the surfaces 398 and 376 while the looper is moving rearwardly out of the needle loops 70 and so hold them until the point of the needle has passed between the looper and a strand of the looper thread. That is to say, the clamp is closed upon each looper thread 399 while the thread remains in the 75 neck 396 of the controller during the backward movement of the loopers, and that portion of each looper thread which extends from the thread clamp through the eye of each looper and up to the preceding stitch 80 is drawn backward free from slack, as shown at 400 in Fig. 22. Immediately upon the point of the needle reaching the position in Fig. 22 the end 358 of the cam contacts with the inclined surface 355 of the lever 351 85 and swings it downwardly to the dotted line position 401, Fig. 22, thereby releasing the grip of the thread clamp upon the looper thread. The cam swings further in the direction of the arrow upon the flat portion 90 356, and thereupon moves backward while the looper is passing from the front to the rear of the needle, thus causing the surface 358 of the cam to travel directly over the surface 357 of the arm 353 to hold it down 95 against the action of the spring 361 until the cam reaches the position in Fig. 21, representing the extreme forward movement of the looper. During this forward movement the thread clamp is held open or released to 100 permit the free movement of the looper thread for the formation of the next stitches.

100 Simultaneously as the loopers reach the end of this forward movement as in Fig. 21, the loopers are shifted from the rear to the front side of the needle, thus shifting the end 358 of the cam off of the surface 357 at which time the spring 361 swings the lever 351 upwardly and closes the thread clamp, holding it closed during the backward movement of the looper out of the needle loops, and until the needle point 110 has passed down between the back of the looper and a strand of the looper thread.

110 The action of the thread controller in conjunction with the thread clamp is such as to act upon the looper threads to take up the slack during the backward movement of the loopers, and simultaneously as the thread clamp opens the loops 400 of the 115 looper threads are in such position where they slide out of the neck 396 over the curved shoulders 395 and during a further backward movement of the loopers the loops 120 are drawn up into the bend 393 of the thread-controller as shown in Fig. 23. The looper threads remain in such position during the forward movement of the loopers, the same drawing the needed thread from 125 the supply through the thread eye 385, and 130

holding the thread so that it will positively draw through the neck 396. As the loopers reach their extreme forward position, as indicated in Fig. 21, and simultaneously as they shift from rear to front of the needles, for the return movement, the thread clamp 374, as hereinbefore described closes upon the threads, and inasmuch as the strands of the looper threads 399, extending from the hole in the wall 380 to the hole in the wall 386, lie in the neck 396, the same are carried downward in an inwardly curving path to the position indicated at 400, whereupon the nipper or thread clamp is released or opens and the threads are cast off, thereby giving the necessary slack thread for the tying of the stitches.

Thus it will be seen that the arrangement of the looper thread controlling parts is such as to positively act upon the looper threads to control the slack, and after the slack has been controlled, the controller 387 reaches a position where the thread is automatically cast out of the neck 396, due to the angular relation between the thread guides and the position the neck 396 assumes after the needle has entered, as in Fig. 22, between the looper and looper thread during the stitch-forming cycle.

Referring to Figs. 3, 5, 17, 25 and 27, in order to conduct the looper threads 399 from the supply to the thread controlling mechanism, two thread tubes 404 are provided which extend from the rear through the machine housing, and through the cylinder 12 where the forward ends 406 terminate close to the thread controlling means. This arrangement offers the advantage of conducting each thread separately from a position close to the supply, through the interior of the machine, and keeps them entirely protected from the operating mechanism and lubricant, and also prevents any lint carried through by the thread from accumulating in the machine. The threads are thus separately encased or housed throughout substantially the length of their travel. Two apertures are provided in the lower portion of the cover plate 7 through which project the ends 403 (Fig. 5) of the thread tubes 404. The bearing 286 is slotted at 405 (Fig. 17) to permit the tubes to pass therethrough one above the other.

The end bearing 248 is also cut out as shown in Fig. 25 to permit the thread tubes 404 to pass between the inside wall of the cylinder 12 and the end bearing. The outlet ends of the tube 406 are located adjacent to the elongated slot 407 provided in the wall of the cylinder 12 to permit threading wires to be inserted in the tubes 404 for drawing the end of the thread through. An angular saw-cut 408 extending from the elongated slot to the edge of the cylinder permits the thread to be placed

in between the wall 376 of the cylinder and the surface 398 of the controller clamp 374.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. In a sewing machine, the combination of a looper shaft, a looper carried by said shaft, means for moving the looper in an elliptical path during its curvilinear movement, and means for imparting to the looper a different elliptical path of movement at an angle to the other to cause the looper to move a greater distance forwardly and a greater distance rearwardly at the opposite ends of its transverse movement into and out of the needle loops.

2. In a sewing machine, the combination of a needle, means for imparting to the looper an elliptical path of movement relatively to the needle, and means cooperating with said means and adjustable to impart to said looper a different elliptical path of movement in which the looper is thereby caused to move a greater distance rearwardly relatively to the needle at one end of its loop taking throw and a greater distance forwardly relatively to the needle at the opposite end of said throw.

3. In a sewing machine, the combination of a machine frame comprising an oil chamber having enclosing side walls, a needle, a looper, means for imparting to said looper an elliptical path of movement relatively to the needle, and means cooperating with said means and accessible for adjustment from the outside of said machine frame for imparting to said looper a different elliptical path of movement in which the looper is thereby caused to move a greater distance rearwardly of the needle at one end of its loop-taking throw and a greater distance forwardly of the needle at the opposite end of said throw.

4. In a sewing machine, the combination of a needle, a looper, means for moving the looper in an elliptical path during its curvilinear movement, and means cooperating with said means for moving the looper in a different elliptical path at an angle to the other in which the looper is thereby caused to move a greater distance rearwardly relatively to the needle at one end of its loop-taking throw and a greater distance forwardly relatively to the needle at the opposite end of said throw.

5. In a sewing machine, the combination

of a looper shaft, a looper carried by said shaft, means for moving the looper in an elliptical path during its curvilinear movement, and means for imparting to the looper a different elliptical path of movement at an angle to the other while maintaining the centers of said elliptical paths approximately the same, said means comprising a pitman, and an adjustable shaft having a swinging fulcrum pivoted thereto and cooperating with said pitman.

6. In a sewing machine, the combination of a needle, a looper, means for moving the looper in an elliptical path during its curvilinear movement, and means cooperating with said means for moving the looper in a different elliptical path at an angle to the other in which the looper is thereby caused to move a greater distance rearwardly relatively to the needle at one end of its loop-taking throw and a greater distance forwardly relatively to the needle at the opposite end of said throw, said means comprising a pitman and an adjustable shaft having a swinging fulcrum pivoted thereto and cooperating with said pitman.

7. In a sewing machine, the combination of a looper shaft, a looper at one end thereof, a crank pin secured to the opposite end of said shaft, a drive shaft, a pitman operated thereby and connected to said crank pin for rocking said looper shaft, a shaft, a swinging fulcrum pivoted thereto and fulcrumed on said pitman, and means for angularly adjusting said last named shaft.

8. In a sewing machine, the combination of a hollow machine frame comprising an oil reservoir having walls enclosing the same against the escape of oil to the outside, a drive shaft, a looper shaft operated from said shaft, means located in said reservoir for adjusting the path of movement of the looper, and means extending through one of said walls and having an oil tight joint therewith for operating said adjusting means from the outside of the machine frame.

9. In a sewing machine, the combination of needle mechanism, a looper, and means for imparting to said looper a four motion path of movement and including means operative to vary said path of movement of the looper to move the looper a greater distance forwardly of the needle at one end of its throw into and out of the needle loops and a greater distance rearwardly of the needle at the opposite end of such throw.

10. In a sewing machine, the combination of a hollow machine frame enclosed on all sides, needle mechanism, a drive shaft, a looper shaft, a looper connected to said shaft, a crank lever within said frame and connecting said shafts a fulcrum shaft, fulcrum means pivoted thereto and cooperating with said lever, and means normally accessible

for adjustment from the outside of the machine frame for angularly adjusting said fulcrum shaft.

11. The combination of needle mechanism, a drive shaft, a looper shaft, a looper carried by said shaft, a lever connecting said drive shaft and looper shaft, a swinging member having a pivotal axis and forming a fulcrum for said lever, and means for angularly adjusting the pivotal axis of said member.

12. The combination of needle mechanism, a drive shaft, a looper shaft, a looper controlled by said shaft, a reciprocating member connecting said drive shaft and looper shaft a swinging member having a pivotal axis and forming a fulcrum for said reciprocating member, said swinging member normally extending at right angles to said looper shaft, and means for adjusting the pivotal axis thereof.

13. In a sewing machine, the combination of needle mechanism, a drive shaft, a looper shaft operated therefrom a looper carried by said looper shaft, means for moving said looper in various angularly related paths, said means comprising a reciprocating lever connected to said drive shaft, an angularly adjustable shaft, and a fulcrum connection between said lever and adjustable shaft.

14. In a sewing machine, the combination of needle mechanism, a drive shaft, a looper shaft operated therefrom, a looper carried by said looper shaft, means for imparting to said looper various elliptical paths of movement, said means comprising a reciprocating lever connected to said drive shaft, a fulcrum member connected to said lever and having a normally fixed pivot, and means for adjusting the axis of said pivot.

15. In a sewing machine, the combination of needle mechanism, a looper, and means for imparting to said looper a four motion path of movement and including means adjustable for varying said movement to cause the looper to move a greater distance forwardly and a greater distance rearwardly at the opposite ends of its transverse movement into and out of the needle loops.

16. The combination of a drive shaft, a looper shaft, a looper carried by said shaft, a reciprocating lever connecting said shafts, a fulcrum member, for said lever, a shaft pivotally supporting said member, and means for angularly adjusting said shaft.

17. In a sewing machine, the combination of a hollow machine frame comprising an oil reservoir having walls enclosing the same against the escape of oil, needle mechanism, looper mechanism including a looper, means for imparting to said looper a four motion path of movement and including means adjustable for varying said path to cause the looper to move a greater distance forwardly and a greater distance rearwardly at the opposite ends of its transverse movement into

- and out of the needle loops, said last means extending through a wall of said frame for access outside the frame.
18. In a sewing machine, the combination of a supporting shaft, a carrier having a central opening provided with a marginal circular flange, a looper comprising a blade offset at its rear end to provide a shank extending rearwardly of the looper blade, said shank having a curved edge seated on said flange, and means for adjusting said looper on said flange. 70
19. In a sewing machine, the combination of a supporting shaft, a carrier comprising a curved body having a central opening and a pair of circular marginal flanges projecting at opposite sides of the body, a pair of loopers adjustably mounted on said flanges at opposite sides of the body, each 80 looper comprising a blade and a shank, the shank having the bottom edge curved concentrically with said flange and seated thereon.
20. In a sewing machine, the combination of a supporting shaft, a carrier mounted on said shaft, a looper adjustably mounted on said carrier at one side of the shaft, and a needle guard adjustably mounted on said carrier at the opposite side of said shaft. 85
21. In a sewing machine, the combination of a supporting shaft, a carrier mounted on said shaft, a looper mounted on the carrier at one side of the shaft, a needle guard mounted on the carrier at the opposite side of the shaft, and means for relatively adjusting said looper and needle guard. 90
22. In a sewing machine, the combination of a supporting shaft, a carrier having a central opening provided with a marginal circular flange, a looper having a curved shank adjustably mounted on said flange, and a needle guard having a curved shank adjustably seated on said flange. 100
23. In a sewing machine, the combination of a looper shaft, a carrier mounted on said shaft, a pair of loopers mounted at opposite sides of said carrier and at one side of said shaft, and a pair of needle guards mounted at opposite sides of said carrier and at the other side of said shaft, said loopers and needle guards having each a shank provided with an arcuate slot to permit adjustment relatively to said carrier. 110
24. As an article of manufacture, a looper having an elongated blade provided with a pair of thread eyes, and a groove therebetween, said groove having an opening of less width than the groove. 120
25. As an article of manufacture, a looper having a curved blade provided with a pair of thread eyes, and a groove therebetween, said groove being closed at one side and having an opening of less width at the opposite side. 125
26. As an article of manufacture, a looper having a blade provided with a pair of thread eyes, a slot connecting said thread eyes, said slot being widened lengthwise thereof to provide a groove overlapped by a longitudinal edge of said slot. 70
27. As an article of manufacture, a needle guard comprising a holder portion, and bent wire formed guard adjustably connected thereto, said holder portion also having a curved supporting portion having a curved slot. 75
28. In a sewing machine, the combination of a machine frame, a hollow oil carrying work arm enclosed against the escape of oil, a bearing at the front end of said arm, a looper shaft journaled in said bearing, and thread nipper mechanism in front of said bearing. 80
29. In a sewing machine, the combination of a hollow oil carrying work arm enclosed against the escape of oil to the outside, a looper shaft therein, a bearing for said shaft at the free end of the arm, thread controlling means at the free end of said arm and comprising actuating means carried by the looper shaft in front of said bearing, and means for conducting thread thru said work arm to the thread controlling means whereby contact of the thread with the oil in the work arm is precluded. 85
30. In a sewing machine, the combination of a machine frame, a hollow oil carrying work arm enclosed against the escape of oil to the outside, a looper shaft extending thru said arm, looper and thread nipper mechanism at the forward end of said arm, and means for conducting thread to said mechanism and cooperating therewith to prevent contact of the thread with the oil in said arm. 90
31. In a sewing machine, the combination of an oil carrying hollow work arm, oil tight to preclude the escape of oil to the outside, looper and thread controlling means at the free end of said arm, means for conducting a flow of oil thru the arm, means for conducting thread thru the arm to said thread controlling means and cooperating with said last means to preclude contact of the thread with the oil. 100
32. In a sewing machine, the combination of a hollow work arm carrying an oil bath and enclosed against the escape of oil to the outside, thread handling mechanism and thread guiding mechanism within said work arm, and means for precluding contact of the oil with the thread within said arm. 110
33. In a sewing machine, the combination of a hollow machine arm, a looper shaft located therein, a looper, a thread take-up member, and means for mounting said looper and member on said shaft and accessible at the free end of said arm. 115
34. In a sewing machine, the combination of a hollow machine arm, a looper shaft 120
- 125
- 130

therein, a looper carrier mounted at the forward end of said shaft, a looper carried by said carrier, and a thread take-up member also carried by said carrier.

5 35. In a sewing machine, the combination of a hollow machine arm, a bearing at the free end thereof, a looper shaft operating therein, a thread take-up member and a looper carried by said looper shaft in front 10 of said bearing and accessible from the free end of said arm.

15 36. In a sewing machine, the combination of a hollow work arm, a looper shaft extending therethrough, a bearing for said looper shaft mounted at the free end of said arm, thread nipper mechanism extending between said bearing and the wall of the work arm, and operating means for said mechanism accessible from the free end of 20 the work arm.

25 37. In a sewing machine, the combination of a hollow work arm, a looper shaft therein, a bearing for said shaft at the free end of the arm, and thread controlling means accessible from the free end of said arm, and comprising a cam carried by said looper shaft in front of said bearing.

30 38. In a sewing machine, the combination of a hollow work arm, a looper shaft, a detachable end cap for said arm, a looper, a thread take-up and a thread nipper all housed within said end cap, and means also housed within said cap and carried by the looper shaft for operating said nipper.

35 39. In a sewing machine, the combination of a hollow supporting member, stitching mechanism, looper mechanism, supported in said supporting member and including a looper shaft, a cam carried by said shaft, a two-arm rock lever located adjacent to the free end of said supporting member, one arm having a cam surface engaged by said cam, and a thread clamp supported by the other arm.

40 40. In a sewing machine, the combination of a hollow supporting member, stitching mechanism, looper mechanism supported in said supporting member and including a looper shaft, a cam carried by said shaft, a two-arm rock lever carried by said supporting member, one arm having a cam surface engaged by said cam, and a thread clamp carried by the other arm, said cam having a four-motion path of movement for rocking said lever.

45 41. In a sewing machine, the combination of a hollow work arm, a looper shaft, a cam carried thereby, a swinging lever engaged by said cam, and a thread nipper shiftably carried by said lever and operated thereby.

50 42. In a sewing machine, the combination of a hollow oil carrying work arm enclosed against the escape of oil to the outside, means for conducting a flow of oil thru

the work arm, and thread control means located within said work arm for handling the thread at the free end of the arm to preclude contact of the thread with the oil in said arm.

70

43. In a sewing machine, the combination of a hollow work arm, a looper shaft, a bearing for said shaft at the free end of the arm, a rock lever pivoted to said bearing, thread nipper means extending between said bearing and the wall of the arm and carried by said lever, and a cam carried by said looper shaft for rocking said lever.

75

44. In a sewing machine, the combination of a drive shaft, a hollow supporting member, looper mechanism supported therein and comprising a looper shaft, a cam carried by said shaft, thread controlling means operated by said cam, and means for imparting a four motion movement to said cam thereby to operate said thread controlling means.

80

45. In a sewing machine, the combination of a hollow work arm, a looper shaft extending therethrough, a bearing at the free end of the arm for said looper shaft, a looper carried by said shaft and a thread controlling member carried by the looper shaft between said looper and bearing and accessible from the free end of said arm.

90

46. In a sewing machine, the combination of a tubular work support, an end cap detachably mounted at the free end thereof, a looper shaft, a looper and a thread take-up carried by said shaft, and housed within said end cap and accessible upon detaching said cap.

95

47. In a sewing machine, the combination of a looper shaft, a swinging thread guide, a thread clamp carried thereby, said guide having an extended arm, and a cam carried by said shaft and engageable with said arm for swinging the same.

100

48. In a sewing machine, the combination of a hollow work arm, a swinging thread guide located therein, means for pivotally supporting said guide to permit the same to swing toward and from the wall of the work arm, a thread clamp pivoted to said guide and cooperating with the wall of the work arm, and means for swinging said guide from the looper shaft.

110

49. In a sewing machine, the combination of a hollow work arm, looper mechanism comprising a looper shaft extending therethrough, a looper carried by said shaft, a rear bearing for said looper shaft detachably connected to the work arm, a front bearing for the looper shaft detachably connected to the work arm, said bearings being detachable to permit the looper mechanism and said bearings to be shifted together into or out of the arm.
